United States Patent Office.

AUGUSTA N. THOMPSON, OF HOLYOKE, MASSACHUSETTS.

Letters Patent No. 96,165, dated October 26, 1869.

IMPROVED BLACKING-BRUSH.

The Schedule referred to in these Letters Patent and making part of the same.

To all whom it may concern:

Be it known that I, Mrs. AUGUSTA N. THOMPSON, of Holyoke, Hampden county, State of Massachusetts, have invented a new and improved Blacking-Brush; and I do hereby declare that the following is a full and clear description thereof, reference being had to the accompanying drawings, and to the letters of reference marked thereon.

In the drawings, the figure represents a side view of my improved blacking-brush.

My invention consists in the attachment of a sponge, A, to the ordinary polishing-brush B, instead of the small brush which is commonly used.

The brush, so formed, is intended to be used, more particularly, in blacking and polishing stoves, and has many advantages over the brush in common use for that purpose. For, in putting on blacking or stove-polish with the sponge instead of a stiff brush of bristles, all spattering of surrounding objects is avoided, and the sponge being soft and yielding, the polish can be more easily applied in the hollows and corners between the reliefs of the casting than with the brush. Again, the polish may be applied to the stove whether the latter be hot or cold, as the sponge will not readily burn or char.

The manner of attaching the sponge is shown in

the drawings. The wire a, passing through the sponge-piece b, and frame of the polishing-brush B, and being fastened beneath by any suitable means, the top loop of the wire, at c, being drawn down tightly enough to prevent its interfering with the article being smeared with the polish or blacking, the sponge can be kept always full of blacking, and when water is applied, it is absorbed into the sponge equally throughout, and dissolves the blacking equally also. But this is not the case with a brush, as no absorption takes place when it is dipped into water, but the surface only is wetted and a small portion of the blacking dissolved, and that washes off, leaving a hard cake of blacking in the middle of the brush, thereby destroying all its elasticity.

Now, having described my invention,

What I claim as new, and desire to secure by Letters Patent, is—

An improvement in "stove-blackening brush," the arrangement and connection of the sponge with its staple a, knob b, in combination with brush B, as shown and described.

MRS. AUGUSTA N. THOMPSON.
